UNITED STATES PATENT OFFICE

2,287,031

APPARATUS FOR THE CONTINUOUS AFTER-TREATMENT OF THREADS

Heinrich Frohwein, Oberbruch, Rhineland, Germany, assignor to North American Rayon Corporation, New York, N. Y., a corporation of Delaware

Application September 15, 1939, Serial No. 295,069
In Germany September 29, 1938

2 Claims. (Cl. 18—8)

The present invention relates to a method and apparatus for use in the continuous after-treatment of threads or yarns, but primarily has for its object an improved method and apparatus for use in the sizing of yarn of artificial origin.

In a co-pending application of August Hartmann et al., Ser. No. 131,942, filed March 19, 1937, now Patent No. 2,194,470, is described a process and apparatus for use in the continuous after-treatment of yarn of artificial origin. In accordance with the disclosure in this application the freshly spun artificial viscose yarn is passed in a helical path over a pair of inclined rollers arranged one above the other. After-treating liquid in the form of diluted sulfuric acid is sprayed upon the upper roller while water at elevated temperature is sprayed upon the lower roller during the passage of the thread thereover.

It has also been proposed to heat the upper portion of the upper roller and to pass the thread over this heating zone in order to dry it. Yarn thus after-treated may be wound up immediately after drying and is then ready for use in the textile converting industry.

For certain uses, however, it is necessary to subject the artificial yarn in addition to the aforementioned after-treating steps to a sizing process prior to drying and further textile handling.

In the continuous after-treatment and sizing of threads in which two rollers are employed as described in the aforementioned co-pending application, the sizing solution is usually sprayed upon the lower roller, while the surface of the upper portion of the top roller is heated in order to dry the after-treated and sized thread prior to winding and thus avoid agglutination of the different thread bodies with one another.

It has been found that the spraying of the sizing solution directly upon the roller is accompanied by various draw-backs. Not only might a splashing of the sizing solution take place but if the supply of solution is not constantly uniform, excessive amounts of solution will be taken up by the thread if the supply is too great. In this case the thread in passing from the lower roller to the upper one will take excessive amounts of sizing solution to the upper roller where it mixes with the sulfuric acid, being sprayed thereon, while the excessive liquid on the lower roller flows back into the wash water and thus becomes lost for further use.

In those instances in which the drying of the thread is carried out on a heated roller im-

mediately after its sizing, incrustation on the heated surface will take place if the thread is loaded with too much sizing solution.

In accordance with the present invention, all of these difficulties are easily overcome by means of a simple method and arrangement. As pointed out above it has been the practice heretofore to spray the sizing solution directly upon the treating roller over which the thread is passed. 10 In accordance with my invention, however, the sizing solution is first fed to a porous body in the form of sponge rubber, felt and the like, which is in contact with the surface of the rotating treating roller and which spreads the sizing solution upon the roller in an evenly distributed thin film.

One object of my invention is to provide a means and method for the continuous sizing of threads whereby a uniform amount of sizing solution is supplied to the thread.

Another object of the present invention is to provide a simple method and means for carrying out the continuous sizing of threads with a minimum of waste of sizing solution.

25 A further object of the present invention is to provide a means which eliminates splashing of the sizing solution on the treating roller and which prevents the formation of incrustations on the heating surface as a result of excessive quantities of sizing solution adhering to the thread.

These and other objects will partly become apparent and partly be pointed out in the following specification and claims when studied in conjunction with the attached drawing in which is shown a side elevation of a single unit of a machine. Such units may be operated individually or may be combined in a long row of units using common drive shafts, etc.

In the drawing, the numeral 1 indicates a spinning nozzle from which is drawn the thread 2.

The nozzle 1 is immersed in the spinning or precipitating bath 3 through which the thread 2 is drawn and coagulated.

45 A roller 4 delivers the thread to the inclined treating cylinders 5 and 6 over which the thread passes in an approximately helical path. These rollers 5 and 6 are also inclined with respect to each other whereby the thread is automatically fed from one end of the rollers to the other end thereof. After leaving the lower roller the thread is passed through a stationary guide 7 and from there to any suitable collecting device (not shown).

55 A diluted sulfuric acid solution or any other

after-treating bath is sprayed upon the top roller 5 from the nozzle 8 while water of elevated temperature is sprayed upon the lower roller 6 by means of nozzle 9. These liquids flow along the surface of the rollers and drip off at the lower edge thereof where they are caught by drip pans 10 provided with drain pipes 11.

Sizing solution is applied to the lower roller through nozzle 12 which is positioned a short distance above the nozzle 9 and which is provided with a valve 13. The sizing solution prior to contact with the lower roller is intercepted by the distributing body 14. This distributing body may consist of any resilient material such as sponge, felt or the like and is held against the lower roller 6 by means of any known resilient support which in the drawing is shown as a coil spring 16 so that a constant contact with the roller is assured. The action of the distributing body may be said to be analogous to that of a wick used in oil lamps or the like.

The upper end of the top roller 5 is provided with a drying zone for the thread. The heating element 15 heats the surface of the roller over which the thread is passed.

The operation of the device illustrated in the drawing is as follows. A spinning solution is extruded through the spinning nozzle 1 and thus the thread 2 is formed which is coagulated in the precipitating bath 3. The guide roller 4 draws the thread from the precipitating bath and passes it to the inclined cylinders 5 and 6. These cylinders are positioned at an angle to each other, and thus the thread is automatically advanced in a helical path from one end of the cylinders to the other. Through nozzles 8 and 9 the thread is treated with after-treating solution and water since the liquids sprayed upon the cylinders 5 and 6 by the nozzles 8 and 9 flow along the surfaces of these inclined cylinders and contact the thread as it passes thereover. Following the water treatment of the thread on the lower cylinder, the thread is subjected to a sizing operation on this cylinder. The sizing solution, the supply of which may be regulated by the valve 13, is extruded through nozzle 12 and is sprayed upon a distributing body 14 which may consist of any resilient porous material such as sponge, felt or the like. The distributing body is held in constant contact with the surface of the lower cylinder 6 by means of any known resilient support. The sizing solution is sprayed upon the upper surface of the distributing body. While seeping through this porous material the sizing solution is distributed uniformly and evenly therethrough and is then fed from the lower surface of the distributing body to the cylinder 6 in an even film. The supply of liquid to the distributing body is regulated through the valve 13 which is connected to the nozzle 12. After the thread has been treated with sizing solution it is passed over the heating zone on the upper cylinder 5 where it is dried, and finally it is led to any suitable take-up or twisting device.

The advantages of this invention are clearly apparent. By using the device illustrated in the accompanying drawing a splashing which might take place is completely eliminated while the formation of incrustations on the drying surface is materially prevented; on the other hand the treatment of the thread with a constantly uniform quantity of sizing solution is assured.

Although my novel process and apparatus have been particularly described with respect to the after-treatment of artificial viscose yarn used in accordance with the so-called continuous wet spinning process, it is to be understood that the invention will yield equally good results in the manufacture of filaments, yarns and threads of other regenerated celluloses, such as, for example, cuprammonium cellulose, cellulose acetates, cellulose ethers, casein fibers, etc.

It is further to be understood that the invention herewith shown and described may also be used in the continuous treatment of threads or filaments with solutions other than a sizing solution.

It is obvious that many variations may be made in utilizing the above invention and it is not intended to limit it to the particular embodiment shown and described. The terms used in describing the invention have been used in their descriptive sense and not as terms of limitation and it is intended that all equivalents thereof be included within the scope of the appended claims.

What I claim is:

1. An apparatus for use in the continuous after-treatment of threads of artificial origin, comprising a pair of inclined rotatable rollers over which the thread is passed, said rollers being arranged one above the other in spaced relation, means to spray after-treating solution upon each 35 of said rollers, means to feed sizing solution to the lower roller, porous means arranged below said feeding means and having resilient contact with the surface of the lower roller adapted to spread sizing solution in a uniform layer upon a predetermined area of the surface of said lower roller, heating means adapted to heat a portion 40 of the upper roller over which the thread is passed, and a take-up device for collecting the thread.

2. An apparatus for use in the continuous after-treatment of threads of artificial origin, comprising a pair of rotatable rollers over which the thread is passed in a substantially helical path, and distributing means adapted to spread 55 a uniform layer of after-treating liquid upon a portion of the surface of one of said rollers, said distributing means comprising a nozzle through which after-treating liquid is extruded, means cooperating with said nozzle to regulate the supply of said liquid, and a porous body resiliently held against the surface of one of said rollers adapted to receive after-treating liquid from said nozzle.

HEINRICH FROHWEIN.
